TUBING BLEEDER FOR OIL WELL PUMPS

Hartley Burton Lee, Berkeley, Calif.

Application November 2, 1940, Serial No. 364,046

11 Claims. (Cl. 137—34)

This invention, a tube bleeder, is specifically designed for bleeding pump columns of oil well pumping systems, though it may also be adapted to pumps for pumping other types of liquids and for draining enclosed pipelines.

For pumping oil from oil wells plunger pumps are customarily used and which are actuated through the medium of a sucker rod which extends down into the string of pipe which forms the pump column and which extends to the surface and from which point it is piped to tanks, sumps, or pipe lines, a walking beam or jack being used to operate the sucker rod.

The string of pipe or column through which the oil is lifted to the surface, particularly in connection with deep wells, is provided with a tubing catcher at its lower end, so that, in the event of breakage or slipping of the tube, the catcher will engage the inside of the well casing and prevent the tube from dropping to the bottom of the well.

In case of such breakage the tube will be suitably drained, but there are many occasions when the tube must be removed, possibly in view of wear of the piston packing, improperly seating valves, sanding or gumming, or for various other reasons, and in such cases the tube remains full of oil during the removal process. This adds the load of the entire tube of oil to that of the tube and pump parts which must be raised from the well, and, as the pump system is lifted from the well the oil contained in the tube is wasted, particularly in view of the fact that the tube must be disassembled section by section, in lengths conforming to the height which the derrick is capable of handling. When it is considered that in some cases these tubes or columns are thousands of feet long and on the average between 2 and 3 inches in diameter, it will be realized that considerable additional weight must be lifted and that considerable wastage of oil results each time the tube is removed from the well.

The objects of the invention; to eliminate this wastage of oil and of the power required to lift this wasted oil to the surface; to make the removal of the tube more convenient and eliminate the major part of the messiness during the operation of uncoupling the sections; to facilitate the operation of removing the tube; to reduce the fire hazard which results from the spillage of oil about the well, and to provide easily operated and economically constructed means for carrying out these objects.

In describing the invention reference will be made to the accompanying drawing, in which:

Fig. 1 is a front elevation of the invention shown in half section, to show both, the interior and exterior construction.

Fig. 2 is a section taken on line 2—2 of Fig. 1.

Fig. 3 is a section taken on line 3—3 of Fig. 1.

The customary oil well pump includes a cylinder with a piston or plunger operating therein and which piston is operated by a sucker rod which in turn is operated by a walking beam or jack. These parts, being well known in the art and not forming a part of the invention through being associated therewith, are not illustrated.

The cylinder (not shown) is located at the lower end of the lower tube 10 and this tube has 15 associated therewith the customary tubing catcher 9 which is well known in the art and which is therefore only roughly indicated. This tubing catcher, as is well known, is brought into immediate action when the tube 10 is suddenly or too rapidly lowered and grabs the inner surface of the well casing 11 and supports the tube, preventing it from dropping down into the well. It also coincidentally locks the tube against rotation, and a slight lift on the tube releases the 20 catcher to permit raising or lowering of the tube.

This invention, the tube bleeder, is located between the lower portion 10 of the tube and the upper portion 12, and preferably immediately above the tube catcher, and forms a part of the 25 string of tubing or pump column. This is clearly indicated in Fig. 1, and the invention consists of a base 13 which is chamfered at its lower end as indicated at 14 to prevent its catching on any joints or other obstructions in the well casing

30 11, and the base has a bore 15 which is substantially equal to the inside diameter of the tube 10, and it also has a threaded counterbore 16 for the threaded end 17 of the lower portion 10 of the string of tubing, and it is reduced in diameter

35 40 and threaded at 18 for connection to the body 19 and also has a shoulder 20 against which the lower end 21 of the body seats to form an oiltight joint. This base has one or more stops 22 which project upwardly from the top surface 23.

45 The body 19 is internally threaded at its lower end as indicated at 24 and is tightly screwed onto the threaded portion 18 of the base; thus the body 19, base 13 and lower portion 10 of the string of tubing are connected into a rigid unit.

50 55 Mounted within the body 19 is a valve 25 which has a seat 26 which has a sealing fit with the seat 27 formed in the body, and alignable ports 28 and 29 are formed respectively through the valve and body, the number and size of ports depending on the rate of bleeding desired. This valve

has an integral stem 30 which has approximately the same internal diameter as the tubing 10-12 and is turned externally and is threaded at its upper end as indicated at 31 for the coupling 32 which connects it to the upper portion 12 of the string or tubing.

The body 19 is bored at 33 to fit the stem 30 and is relieved at 34 and bushed at 35 to form a bearing and secondary oil seal, and has double inclined clutch teeth 36 formed at its upper end. Thus the valve 25 and stem 30 are rotatable within the body and relative to the lower portion 10 of the string.

One or more stops 37 are formed on the lower end of the valve and depend from the lower surface thereof for cooperation with the stops 22 one stop being shown for cooperation with two stops 22 on the base 13, and these stops are so related that when the stops cooperate in one position, the ports 28 and 29 will be in registry, and when they cooperate in the other position all ports 28 and 29 will be out of registry and will be sealed by the valve faces 26 and 27.

Rotatably and slidably mounted on the stem 30 and located above the body is a clutch block 38 which has teeth 39 formed at its lower end for cooperation with the teeth 36 formed at the upper end of the body, and suitable slots 40 are formed at the upper end for sliding cooperation with the tongues 41 which depend from the thrust collar 42 and which is slidable but non-rotatable on the stem 30, rotation being prevented by the key 43 or other suitable means. The upper end of this thrust collar is chamfered at 44 to prevent catching on the joints of the well casing 11, and compression springs 45 are mounted in bores 46 and 47 formed respectively in the clutch block and thrust collar. A contractile ring 48 is seated in a groove 49 formed in the stem 30 and retained within the counter-bore formed at the upper end of the thrust collar, for limiting the upward movement of the thrust collar under the urging of the springs 45.

The operation of the invention is as follows: During normal pumping operations the stop 37 rests against the other stop 22 from that with which it rests in Fig. 3 and the port 28 is located 90° from the position shown in Fig. 1 and the port 29 is sealed by the face 26 of the valve. Thus there can be no leakage of oil from the inside of the tube or column, the oil being pumped up through the internal passage 50 through the valve stem.

If it becomes necessary to remove the string of tubing, the string is disconnected at the surface while being supported by the rigging. It is then quickly or somewhat suddenly lowered to a slight extent to cause the tubing catcher to grab the casing 11 thus supporting the entire string and coincidentally locking the tube catcher section 10 against rotation relative to the well casing.

The upper section 12 at the surface is then rotated through a portion of a revolution, causing the teeth 39 to ride over the teeth 36 until the stops 22 and 37 cooperate as indicated in Fig. 3, thus aligning the ports 28 and 29 as indicated in Fig. 1 and permitting the oil within the string of tubing to drain out into the surrounding well casing.

The string can now be raised and disconnected section by section, and during the process of raising, grabbing and disconnecting a section, the oil in the balance of the string will have had ample time to drain from the next section to 75

be removed and which when raised may be disconnected without the loss of any oil because the oil will have drained back into the well, making the job far cleaner with no oily mess around the well, while reducing the amount of power required and eliminating wastage of oil.

When the string of tubing is to be replaced, the stem of the valve is turned by means of the portion 51 to the position where the ports 28 and 29 are sealed as previously explained and the first section is connected to the valve stem, lowered, and followed by the succeeding sections until the entire string is back in place in the well.

Unless the lower section is held by some means, the entire string of tubing will rotate because the teeth 36 and 39 backed up by the springs 45 will prevent any other than forced rotation of the upper portion 12 relative to the lower portion 10. The tongues 41 and key 43 together with the springs 45 and teeth 36 and 39 all cooperate to maintain the relation between the two portions of the string.

The clutch in combination with the springs, tongues and key maintains the relation between the ports 28 and 29 whether in open or closed position, and when the two portions are forcibly rotated one relative to the other, the stops 22 and 37 assure respectively full opening of the ports or complete sealing thereof. It prevents rotation of one relative to the other under any other conditions, so that the ports cannot be accidentally closed while the string is being raised from the well or while the pump is in operation.

I claim:

1. A tube bleeder for a string of tubing comprising; a device coupled in the string intermediate its length and forming a coupling and consisting of an internal member terminating at its lower end in a valve, and an external member rotatable on said internal member and having a valve seat formed therein, said members being rotatably mounted one within the other and coupled together and respectively connected to the upper and lower portions of the string and including, ports formed through said valve and said seat controlled thereby and draining to the exterior of the device when the ports are opened by said valve, said ports being adjusted to open and closed positions through rotation of one portion of the string relative to the other while maintaining the valve constantly seating on the seat, said valve functioning as the sole support for the external member and the lower portion of the string of tubing, through cooperation with said seat.

2. A tube bleeder for a string of tubing consisting of two portions comprising; a device forming an intermediate section of said string and coupling the two portions together and comprising two members relatively rotatable one within the other and forming in combination a valve and a seat; alignable ports formed through said valve and through said seat and providing communication between the interior and the exterior of the device when the two members are in one relative position and being sealed by said valve when said two members are in another relative position; rotation of one of said portions relative to the other changing said relative positions for drainage or nondrainage, said valve cooperating with the undersurface of the portion of one member which forms said seat and functioning as the sole support for the one member and the lower portion of the string of tubing through suspending

cooperation, and forming an efficient seal between the valve and its seat through the weight of said one member and the lower portion of the string.

3. A tube bleeder comprising an upper and a lower tubular element, with the upper element rotatable within the lower element, said upper element terminating at its lower end in an annularly-projecting valve with the valve face formed on the upper surface, and a valve seat formed interiorly of said lower element for cooperation with said valve face and ports controlled by said valve and seat for draining fluid from the interior to the exterior of the bleeder or maintaining the fluid against drainage, at will; said elements being adjustable to two positions respectively for opening and closing said ports through relative rotation of one element to the other, and means releasable through predetermined torque differential between the respective elements maintaining the relative positions under normal conditions or torque applied with a value less than said predetermined differential, said lower element being suspendedly supported and having its sole support through said valve and valve seat and functioning to maintain constant contact between the valve and its seat.

4. A tube bleeder for a string of tubing comprising; two tubular elements rotatable one within the other and consisting of an outer element and an inner element and including valve means and ports controlled thereby for communication between the interior of the inner tubular element and the exterior of the outer tubular element; said valve means including a valve and its seat forming locking means for locking the elements together and supporting means for sole support of the lower portion of the string by the inner tubular element; said elements having connecting means for connection within the string of tubing; rotation of one element relative to the other in one direction aligning said ports for drainage of fluid, and in the other direction sealing said ports against drainage; stop means associated with said elements for limiting the degree of rotation in either direction; and means associated with said elements maintaining the relative positions of said ports under normal operating conditions and releasing under predetermined torque differential applied to the respective elements.

5. A structure as defined in claim 4 in which said tubular elements consist respectively of an axial base having said stop means included therewith and a passage and securable to the lower portion of the string of tubing and with the outer tubular element attached thereto said valve means consisting of a conical valve seat formed internally of said outer element with said ports formed within the limits of said seat, and said inner tubular element terminating at its lower end in an annularly projecting conical valve; a tubular stem for said valve and rotatable in said outer tubular element and seating on said seat and with said ports formed within the confines thereof and including means for attaching said stem to the upper portion of the string.

6. A tube bleeder for bleeding liquid from a string of tubing consisting of an upper portion and a lower portion, comprising; a base having a fluid passage therethrough and attached and sealed to said lower portion; an outer tubular element sealed to said base and counterbored at its lower end and terminating in an internal coni-

cal valve seat and outer ports formed through the wall of said tubular element within the confines of said seat; an inner tubular element rotatable in said outer element and terminating at its lower end in an annularly projecting conical valve seating on said seat and having inner ports formed therethrough and alignable with said outer ports; said valve forming locking means for locking the two elements together and forming the sole support for suspendedly supporting the lower portion of the string by said inner tubular element; said inner tubular element having means for attachment to the upper portion of said string; rotation of one element relative to

the other aligning said ports in a predetermined position and sealing said ports in another position; suspended support of the lower portion of the string by the inner element functioning to efficiently seat said valve through application of the weight of said outer tubular element and the lower portion of the string.

7. Coupling means for coupling two portions of a string of tubing comprising; two tubular elements one rotatable within the other and respectively connected to the two portions and including an outer element and an inner element and locking means coincidently forming valve means including a conical valve and a seat formed respectively on said inner and outer elements; alignable ports formed through said valve and said seat; stops formed on said elements for cooperation for alignment and non-alignment of said ports; and a clutch releasable under predetermined torque differential for maintaining the relative positions of said ports under normal operating conditions and torque differentials; said valve and seat being adapted to function as the sole support for the lower portion of the string by said inner element with the total weight of the lower portion operating to seat the valve on its seat.

8. A tubing bleeder comprising; a first tubular element attachable to the lower end of the upper portion of a string of tubing and terminating at its lower end in an annular flange with a first valve seat formed on its upper surface; a second tubular element attachable at its lower end to the upper end of the lower portion of the string of tubing and having a counterbore in its lower portion terminating in a second valve seat for cooperation with said first valve seat; alignable passages formed through said valve seats for draining fluid from the inside of the first tubular element to the outside of the second tubular element; said second tubular element being suspendedly supported through said flange and top of said counterbore through cooperation between said valve seats, and said first tubular element being rotatable within said second tubular element, and means included for limiting the relative rotation of said elements.

9. A tubing bleeder comprising; an outer tubular element attachable at its lower end to the upper end of the lower portion of a string of tubing and having a counterbore formed upwardly from its lower end terminating in a conical valve seat; an inner tubular element rotatable in said outer element and attachable at its upper end to the lower end of the upper portion of the string of tubing and terminating at its lower end in an annularly projecting flange formed with a mating conical valve face on its top surface for cooperation with said valve seat and forming suspending means for the outer element with the weight of the outer element being adapted to

create intensive and positive cooperation between the face and the seat for efficient sealing; and ports alignable through rotation of the inner element relative to the outer element and formed through said inner and outer elements within the confines of said face and said seat.

10. A tube bleeder comprising; a first tubular element having means at its lower end for connection to the lower portion of a string of pipe and counterbored upwardly from its lower end and terminating at the upper end of the bore in a valve seat; a second tubular element rotatable in said first tubular element and having means at its upper end for connection to the upper portion of the string of pipe and terminating at its 15 lower end in a flange rotatable in said counterbore and with a valve face formed on the upper surface of the flange for cooperation with said valve seat; said first tubular element functioning as a valve stem for the valve formed by said flange and as a support for the second tubular element and the lower portion of the string of pipe; alignable passages formed through both elements; said valve face and seat cooperating to seal said passages against escape of fluid from the inside of the first tubular element to the outside of the second tubular element when the tubular elements are in one relative position, and opening said passages for escape of fluid when one of the tubular elements is rotated to another position relative to the other tubular element, and breaking the seal between the valve face and its seat in the event of breakage of the upper portion of the string and thereby draining the upper portion of the string.

35

11. A tube bleeder comprising; a sleeve having a counterbore formed upwardly from its lower end and terminating at the top of the counterbore in a conical valve seat; a second sleeve rotatable in said first sleeve and terminating at its lower end in a flange rotatable within said counterbore and having a conical top face for cooperation with said conical seat and forming a valve with said second sleeve functioning as the valve stem; and a stop element depending from the bottom of said flange, and means for sealably securing the upper end of said valve stem to the upper portion of a string of tubing; a connection sealably connected to the lower end of said first sleeve and having means at its lower end for sealable connection to the lower portion of the string of tubing, and having an internal diameter less than that of the first sleeve and having a stop member on its top surface for cooperation with said stop element to limit the degree of rotation of said valve relative to its seat; passages formed respectively through both sleeves within the confines of the seating surfaces of said valve and its seat; and alignable through limited rotational adjustment of one sleeve relative to the other; and clutch means cooperating between said sleeves and urging maintenance of the existing relation between the sleeves and the relative adjusted relation between the passages, differential torque applied between the sleeves overcoming said urge for adjustment of the sleeves and passages one relative to the other.

HARTLEY BURTON LEE.
